Primary Examiner — Derrick Holland(74) *Attorney, Agent, or Firm* — Gottlieb, Rackman & Reisman, P.C.(57) **CLAIM**

The ornamental design for a charging system, as shown and described.

DESCRIPTION

FIG. 1 is a bottom, front, left side perspective view of a charging system having the design of my invention;

FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a bottom plan view thereof; and,

FIG. 8 is another bottom, front, left side perspective view thereof.

The broken lines shown represent unclaimed subject matter and form no part of the claimed design.
